CLAIM

The ornamental design for a pallet rack repair structure, as shown and described.

DESCRIPTION

FIG. 1 is a perspective view of the pallet rack repair structure;

FIG. 2 is a side elevational view thereof as seen from the left hand side of FIG. 1;

FIG. 3 is a front elevational view thereof;

FIG. 4 is a top plan view thereof;

FIG. 5 is a bottom plan view thereof;

FIG. 6 is a side elevational view thereof as seen from the right hand side of FIG. 1; and,

FIG. 7 is a rear elevational view thereof.
